Joseph Lewis:

UNITED STATES PATENT OFFICE.

JOSEPH LEWIS, OF CHICAGO, ILLINOIS.

PNEUMATIC GRAIN-ELEVATOR.

SPECIFICATION forming part of Letters Patent No. 285,047, dated September 18, 1883.

Application filed June 29, 1883. (No model.)

To all whom it may concern:

Be it known that I, JOSEPH LEWIS, a subject of Great Britain, residing in Chicago, in the county of Cook and State of Illinois, have 5 invented a new and useful Improvement in Pneumatic Grain-Elevators, of which the following is a specification.

My invention relates to methods of transferring grain and similar articles by pneumatic 10 action; and it consists, first, in the employment of a direct carrying-blast leading to the point of delivery, and an induced current due to said blast, whereby the grain is sucked into the blast and transferred thereby.

15 The invention further consists in the employment, in the transfer of grain by pneumatic force, of a blast of hot air, whereby the passages through which the blast leads are kept warm, so that the blast is naturally increased 20 in strength and the grain is dried.

The invention further consists in the apparatus hereinafter described, whereby the above features of invention are carried out, and also in further mechanical features, also set forth 25 below.

In the drawings, Figure 1 is a sectional elevation of an elevator to which grain is being transferred by my apparatus. Fig. 2 is a plan view of the vacuum-chamber. Fig. 3 is a 30 sectional view of a grain-car adapted to be used with my invention. Figs. 4 and 5 are detail views of the hand-nozzle and vent sometimes used, and Fig. 6 is a vertical section of the vacuum-chamber.

35 In said drawings I have shown the apparatus as employed in connection with an elevator-building, A, having a bin, A', into which the grain is being transferred by my apparatus from the railroad-car B.

40 The apparatus consists of a compressed-air-supply pipe, C, leading from an air-reservoir, C', or from a compressor, and having a regulating-valve, c, a vacuum-chamber, D, into which said tube discharges, the blast grain-carrying pipe E, opening from said vacuum-chamber and leading to the receiving-bin or other receptacle into which the grain is to be transferred, and conduits F, one or more, leading from the car B or other grain-receptacle 45 from which the grain is to be transferred, and discharging into the vacuum-chamber. The inlets and outlets for the air and grain in the

vacuum-chamber are arranged somewhat on the injector principle, as clearly illustrated in Fig. 1, where the nozzle c' of the air-supply pipe is carried up into the mouth of the blast-pipe E, so that the blast will be delivered wholly into the latter and not seek escape into the surrounding chamber. This creates a vacuum below said nozzle and in said chamber, and induces a current through the conduits F, which sucks the grain from the car into the vacuum-chamber, from whence it is drawn into the blast-pipe E, and thereby transferred into the elevator.

55 The air used to create the blast I prefer should be heated, for the following reasons: The grain will thereby be warmed and dried to some extent, the volume of the air actually employed will be greatly expanded and the amount thereof required to be compressed be correspondingly lessened, the induced suction will be more powerful, and the force of the upward current will naturally be greater than that of cold air.

60 I have not shown the air-supply pipe as connected to any heating or compressing apparatus; but it will be understood that any known means may be used for those purposes.

65 The conduits F are preferably of flexible tubing—in part, at least—and jointed to the vacuum-chamber cover by screw-couplings f, as shown, and they may be attached temporarily and during the unloading of the car to the bottom thereof by similar couplings. Several 70 of them may open into one chamber, and all should be provided with valves f', whereby they may be closed and regulated.

75 It is desirable that railroad-cars be built with self-discharging bottoms, as thereby the labor of shoveling when unloading is lessened. They may for this purpose be provided with floors inclined from the sides to the center, as shown in Fig. 1, and in such case openings at the apex of the angle formed by the floor are 80 made, to which the conduits F are secured, as shown in said figure. These openings are closed, when not in use, by valves m, and the volume of the discharge may be controlled by such valves also. Where the flat-bottomed 85 car is to be unloaded through the floor, openings are made therein, which are to be covered, when the car is used for other kinds of freight, by grates or other covers, o. Beneath these 90

openings are secured funnels o' , in which are similar valves, m , and to these funnels the conduits F are removably attached by couplings f or other suitable devices.

5 I have shown the conduits F as drawing grain from the bottom of the car, and such I deem to be the preferable mode of unloading; but in that method it is necessary to supply air to the point from which the grain is drawn, 10 instead of relying upon its passage to said point through the mass of grain lying above it. To insure this air-supply I place in the car an air-tube, G , over each discharge-opening in the floor thereof, such tube extending 15 from above the level of the grain down to immediate proximity with the opening, as clearly illustrated in Figs. 1 and 3. This tube may extend up through the roof, and the amount of air admitted be controlled by a valve or 20 register, g , located at its top. Of course I do not wish in all my claims to be limited to this particular form of suspended air-vent, as it is obvious that openings might be made in the side of the funnel, or the coupling or side tubes 25 be employed to admit or conduct the air to the bottom of the grain.

If it is not practicable to unload from the bottom of the car or other receptacle in which the grain may be stored, then I attach to the 30 conduits F nozzles, which are intended to be inserted in the mass of grain from above, and which may be held in the hand. These nozzles are of peculiar construction, and consist of the nozzle proper, H , which is secured to 35 the end of and is a continuation of the conduit, one or more vent-tubes, $H' H'$, placed parallel to the nozzle and extending down to the orifice thereof, and an inverted conical cap, H^2 , secured to the lower extremity of the nozzle and 40 vent-tubes, as illustrated. This cap is useful to prevent grain entering the vent-tubes when the nozzle is pushed down into the grain, and the vent-tubes supply air to the orifice of the nozzle in the same manner the vents G supply 45 it to the funnels at the floor of the car, already described. The top of the cone is of course open to admit the grain, and the vent-tubes may be regulated by valves h , if desired.

While I have chosen to illustrate my invention as used in transferring from a car to an elevator, it will be understood that it is equally adapted to transfer grain from one car to another and from any receptacle to another; also, that the entire apparatus may be mounted 55 upon a car or vessel, and be moved about from place to place, as required.

When the cars are provided with self-discharging bottoms, as in Fig. 1, they may be provided with false bottoms when it is desired to carry other kinds of freight.

60

I reserve for a future application all claims to which I may be entitled upon the cars herein shown, and the method of venting the withdrawal of the grain, and upon the hand-nozzle also described.

65

I claim—

1. The improved method of transferring grain by pneumatic action, consisting in feeding the grain to the blast by a suction-current lateral to and induced by said blast, substantially as specified.

70

2. The improvement in methods of transferring grain by pneumatic action, consisting in carrying it by a blast of hot compressed air, substantially as specified.

75

3. The apparatus for transferring grain, consisting of an air-supply pipe, a vacuum-chamber, and a blast-conduit, said pipe, chamber, and conduit forming the air-passage of the apparatus, in combination with a suction-conduit lateral to and opening into said passage, substantially as specified.

80

4. The combination, with the compressed-air supply tube, of the vacuum-chamber, the blast-conduit, and suction-conduit, the orifices of the air-supply tube and the blast-conduit into and from the vacuum-chamber being relatively arranged after the manner of an injector, substantially as specified.

85

5. The improved method of transferring grain by pneumatic action, consisting in the employment of a driving carrying-blast leading to the point of delivery, and an induced current due to said blast, whereby the grain is sucked into the blast and transferred thereby, substantially as specified.

90

6. In pneumatic transfer apparatus, the combination, with a blast-conduit conducting the blast from the air-supply to the point of delivery, of a lateral or branch pipe leading from the discharging grain-receptacle into said blast-conduit, whereby the suction induced by the current is utilized to draw the grain into the blast, and the blast itself is utilized to carry it the remainder of the distance, substantially as specified.

100

JOSEPH LEWIS.
